UNITED STATES PATENT OFFICE.

LE ROY FLETCHER SNAPP, OF BROOKLYN, NEW YORK.

SWIMMING APPLIANCE.

Application filed May 1, 1925. Serial No. 27,280.

To all whom it may concern:

Be it known that I, LE ROY FLETCHER SNAPP, a citizen of the United States, and resident of Brooklyn, county of Kings, State of New York, have invented an Improvement in Swimming Appliances, of which the following description, in connection with the accompanying drawing, is a specification, like characters on the drawing representing like parts.

This invention relates to a swimming appliance and particularly to a device of that character which includes a body adapted to be secured to the palm of the hand and wings extensible on either side of the body in planes parallel to the plane of the body.

One of the objects of my present invention is to provide an improved swimming appliance of this type which is simple in construction and comprises few parts.

Another object of the invention is to provide a swimming appliance of this type in which the spreading and closing of the wings may be accomplished by movement of the fingers of the hand to which the device is secured. When a person is swimming he naturally opens his fingers during the propelling stroke and closes them during the return stroke. My improved swimming device is devised so as to make use of this natural movement of the fingers in spreading and closing the wings, said device being constructed so that when the fingers are straightened the wings will be extended or expanded while when the fingers are closed the wings will be folded or closed. The use of the device, therefore, involves simply the natural movement which a person makes in swimming, this natural movement of the hands and fingers resulting in opening and closing the wings.

In order to give an understanding of my invention I have illustrated in the drawings some selected embodiments thereof which will now be described after which the novel features will be pointed out in the appended claims.

Fig. 1 is a view of a swimming appliance embodying the invention showing the wings closed and illustrating the position of the fingers corresponding to this position;

Fig. 2 is a similar view showing the wings opened and showing the fingers straightened;

Fig. 3 is a view similar to Fig. 2 but showing a different embodiment of the invention,

said figure being partially broken away to better illustrate the construction;

Fig. 4 is a view showing the manner in which the device is strapped to the hand;

Fig. 5 is a section on the line 4—4, Fig. 1 showing in full lines the position of the parts when the wings are closed and in dotted lines the position of the parts when the wings are opened or spread;

Fig. 6 is a section on the line 6—6, Fig. 5;

Fig. 7 is a section on the line 7—7, Fig. 6;

Fig. 8 is a fragmentary perspective view showing the form of actuator illustrated in Fig. 3.

The device herein shown comprises a body or frame member 1 which is adapted to be secured to the palm of the hand of the wearer, and two wing members 2 and 3 which are pivoted to the body member 1 at 4 and 5 respectively and which are adapted to swing in planes parallel to the body member 1. These wing members are so constructed that when they are folded as shown in Fig. 1 they are located within the limits of the body member 1 while when they are spread or expanded they extend considerably beyond the body member as shown in Figs. 2 and 3.

The body member may conveniently be made of sheet metal and it is provided at one end with an anchoring flange 18 between which and the body the wings are received, the pivot pins 4 and 5 extending from the flange 18 to the body. On the opposite edge the body is provided with the guiding flange 6 which overlies the wings 2 and 3 and guides them during their swinging movement.

As stated above the opening and closing of the wings is secured by an opening and closing movement of the fingers 7 of the hand on which the device is worn. The means for thus actuating the wings will be presently described.

The device is adapted to be worn on the palm of the hand and may be secured to the hand by various means without departing from the invention. One convenient means for this purpose comprises a strap 8 which is passed under a plurality of loops 9 which are struck up from the body 1, said strap being threaded through the loops in such a way as to form a permanent loop 10 which encircles the hand at the base of the fingers and another loop 11 which encircles the hand opposite the palm thereof. The loop

11 is formed by detachably securing together the two ends 12 and 13 of the strap by means of a buckle 14.

33 indicates a tab which is secured to the buckle and by which the latter may be readily loosened. The buckle will preferably be of the familiar type which includes a toothed actuating member 34 that engages the end 12 of the strap and this buckle may be loosened by simple pulling on the tab 33. The advantage of this construction is that the swimmer can easily loosen the buckle and thus divest himself of the swimming appliance if he so wishes by simply gripping 15 the tab 33 with his teeth and pulling. This can be done during the swimming operation and in an instant's time.

The size of the body 1 is such that the fingers 7 project beyond the body as seen 20 clearly in Figs. 2, 3 and 5 so that the presence of the swimming appliance on the hand does not interfere with opening and closing the fingers. As stated above means are provided whereby the wings 2 and 3 may be 25 spread or closed by the opening and closing movement of the fingers. This is herein provided for by means of an actuating member 15 which is slidably mounted on the body 1 and is pivotally connected to the wings, said 30 actuating member having a loop 16 through which the fingers may be passed.

This actuating member 15 extends through a slot 17 formed in the guiding flange 6 and it overlies the wings as shown in Figs. 1 and 35 2. Said member also extends under anchoring flange 18 and is provided with a slot 19 which receives a guiding stud or post 20 that connects the anchoring flange 18 and the body 1. In the construction shown in Figs. 40 1, 2 and 6 this actuating member 15 is pivoted to the wings at 21 and 22 respectively so that when the actuating member 15 is 45 moved in the direction of its length the wings will be turned about their pivots 4 and 5. This movement of the actuating member is accomplished by opening and closing the fingers.

Assuming the parts are in the position shown in Fig. 1 and full lines Fig. 5 the fingers 7 of the hand will be closed over the edge of the swimming appliance. When the fingers are straightened, as shown in Fig. 2, and also as shown in dotted lines Fig. 5, the actuating member 15 will be drawn outwardly and by its pivotal connection with the wings will operate to swing them outwardly or spread them as shown in Fig. 2. A closing movement of the fingers will obviously return the parts to the position shown in Fig. 1 with the wings folded. The spreading and folding of the wings, therefore, is accomplished simply by the opening and closing movement of the fingers, and as stated above this is a movement which one naturally makes when swimming.

In order to allow free swinging movement of the wings I will preferably provide a pin and slot connection between the actuator 15 and each wing. The pins 21, 22 may be mounted either in the wing or in the actuating member, the other member being slotted to receive the pin. In the construction shown in Figs. 1, 2 and 6 the pivot pins 21 and 22 are in the wings and the slots are in the actuator but so far as this invention is concerned the slot might be in either member.

In Figs. 3 and 8 I have shown a different embodiment of the invention which involves a different form of connection between the actuator 15 and the wings. In this embodiment of the invention each wing is provided near its pivotal end with a tooth or projection 46 and the actuator is formed with two recesses 47 which receive the teeth 46. When the actuator is moved downwardly from the position shown in Fig. 3 the walls 48 of the recesses will engage the teeth and operate to swing them into the dotted line position Fig. 3 thus folding the wings and when the actuator is drawn outwardly into the full line position the walls 49 of the recesses will act on the teeth or projection 46 thus swinging the wings outwardly. In some respects this construction is preferable to that shown in Figs. 1 and 2 because it is less expensive to manufacture.

I may, if desired, employ a spring such as shown at 50 in Figs. 1, 2 and 6 or as shown at 51 in Fig. 3 for assisting in opening the wings. This spring will preferably be confined between the wall 26 and the end of the actuator. The latter may conveniently be formed with a pocket or recess to receive the spring. The spring acts against the actuator tending normally to force it upwardly and thus open the wings.

The muscular force which a person asserts in closing the fingers is stronger than that in opening the fingers and the spring 50 or 51 augments the muscular action of the fingers in opening the wings. The addition of this spring, however, is not necessary to the invention as the device can be operated without it. Under some circumstances, however, it may be desirable to employ such a spring.

In order to permit the wings to be fully folded without interference they are made of the special shape shown. Each wing has the convexly-curved edge 23 on its outer face and the re-entrant portion 24 on its inner face, the latter forming a guiding finger 25. When the device is fully folded the finger 25 of each wing rests against the end wall 26 as shown in Figs. 1 and 6 and the re-entrant portion 24 accommodates the guiding part 20.

The dimensions of the wings are such that when they are folded they come entirely within the outline of the body 1. When the wings are spread as shown in Fig. 2 the finger portions 25 of the two wings overlap

each other and the edges of the wings are confined beneath the guiding flange 6.

In order to provide proper spacing of the wings and other parts I propose to upset 5 the body 1 and the anchoring flange 18 as shown at 27 at the points where the wings are pivoted, these upset portions making bosses which engage the wings and hold them properly positioned. The pivotal connection 10 may be made by means of rivets as shown at 5 in Fig. 5.

The actuating member 15 is provided with stop shoulders 31 which by their engagement with the wall 32 of the body limit the 15 outward movement of said actuator.

While I have illustrated herein some selected embodiments of my invention I do not wish to be limited to the constructional features shown.

20 I claim.

1. A swimming appliance comprising a body adapted to be secured to the palm of the hand, wings pivoted to the body and swingable in planes parallel thereto, and 25 means to open and close the wings by an opening and closing movement of the fingers.

2. A swimming appliance comprising a body adapted to be secured to the palm of the hand, wings secured to the body and extensible and foldable in planes parallel to the plane of the body, and means to extend or close the wings by movement of the 30 fingers.

3. A swimming appliance comprising a body, means for securing said body to the palm of the hand, wings secured to the body and which are extensible and foldable in planes parallel to the plane of the body, 35 an actuator for operating the wings constructed to be given its operative movement by the fingers of the hand.

4. A swimming appliance comprising a body, means for securing said body to the palm of the hand, wings pivoted to the body and swingable in planes parallel thereto, 45 an actuator movable relative to the body and having a loop through which the fingers

may be inserted, movement of the actuator due to opening and closing the fingers causing the wings to be extended or contracted.

5. A swimming appliance comprising a body adapted to be secured to the palm of the hand, wings pivoted to the body and swingable in planes parallel thereto, an 55 actuator slidably mounted on the body and having a loop through which the fingers may be inserted, whereby opening and closing movement of the fingers will give movement to the actuator, and a connection between the actuator and the wings.

6. A swimming appliance comprising a body, means for securing the body to the palm of the hand, wings pivoted to the body and swingable in planes parallel thereto, an actuator slidably mounted on the body, a loop carried by the actuator and through which the fingers may be inserted, whereby opening movement of the fingers moves the actuator outwardly and closing 70 movement of the fingers moves the actuator inwardly, and a connection between said actuator and the wings by which outward movement of the actuator opens the wings and inward movement thereof closes the 75 wings.

7. A swimming device comprising a body, means to secure the body to a person's hand, wings carried thereby and movable relative thereto into either extended position in 80 which they extend beyond the body or into folded position in which they do not so extend, and means for folding and extending the wings by the closing and opening movement of the hand.

8. A swimming device adapted to be secured to a person's hand, said device being expandable and contractible in a plane parallel to the palm of the hand thereby to increase and decrease its resisting surface, and 90 means to expand and contract said device by the opening and closing movement of the fingers of the hand.

In testimony whereof, I have signed my name to this specification.

LE ROY FLETCHER SNAPP.
